UNITED STATES PATENT OFFICE.

JOSEPH WOLNY, OF SHERIDAN, WYOMING.

BEET TOPPER.

Application filed September 12, 1923. Serial No. 662,286.

To all whom it may concern:

Be it known that I, JOSEPH WOLNY, a citizen of the United States, residing at Sheridan, in the county of Sheridan and State of

Wyoming, have invented a new and useful 5 Beet Topper, of which the following is a specification.

This invention aims to provide improved means for cutting the tops off the beets, to 10 provide improved means for guiding the beet tops into the field of operation of the cutting means, to provide novel means for carrying away the tops of the beets, and, to improve generally and to enhance the utility 15 of devices of that type to which the invention appertains.

With the above and other objects in view, which will appear as the description proceeds, the invention resides in the combination 20 and arrangement of parts and in the details of construction hereinafter described and claimed, it being understood that, within the scope of what is claimed, changes in 25 the precise embodiment of the invention shown can be made without departing from the spirit of the invention.

In the accompanying drawings:

Figure 1 shows in side elevation, a device 30 constructed in accordance with the invention, parts being broken away; Figure 2 is a top plan, parts being broken away; Figure 3 is a cross section on the line 3—3 of Figure 1; Figure 4 is a fragmental longitudinal section taken through the topping 35 mechanism, most parts appearing in elevation; Figure 5 is a bottom plan of the shoes of the topper; Figure 6 is a longitudinal section of the cross chute; Figure 7 is a section on the line 7—7 of Figure 1.

The machine embodies an upwardly arched axle 1 of common form. A main frame 2 is provided, the main frame including upper longitudinal bars 3 and lower longitudinal bars 4. The upper longitudinal 45 bars 3 are mounted on the crown of the axle 1, whereas the lower bars 4 are mounted on the ends of the axle 1. The bars 3 are connected by a rear cross bar 5 and by other cross bars 6, 7 and 8; the bar 50 8 being located adjacent to the forward end of the machine.

A draft yoke 9 is attached to the forward 55 ends of the lower longitudinal bars 4. Passing to Figure 3, it will be noted that the bars 4 and 3 of the main frame are connected adjacent to their forward ends, by up-

rights 10 carrying outwardly extended fingers 11 which may be provided with spacing shoulders 12, the fingers being held in place on the uprights 10 by nuts 14.

The machine embodies an upright auxiliary frame 15, shown in detail in Figure 3, and appearing in side elevation in Figure 1. The auxiliary frame 15 includes a top piece 16 and side pieces 17, the parts 17 and 60 16 being connected in any suitable way, as shown at 18. Horizontal longitudinal bars 19 are secured to the lower ends of the side pieces 17 and carry depending rear arms 20 through which extends a rod or support 21. 65 (Figures 4 and 5). The side pieces 17 carry inwardly extended brackets 23. Hangers 22 are provided and are equipped at their upper ends with outwardly extended arms 24, having slots 25 which receive, for adjustment, clamping devices 26 engaged with the brackets 23. The side pieces 17 of the auxiliary frame 15 have vertically elongated slots 27 receiving the fingers 11 slidably, the spacing shoulders 12 being interposed between the parts 17 and 10, and the construction being such that the forward end of the main frame 1 may be adjusted vertically 70 with respect to the auxiliary frame 15.

The means for raising and lowering the 85 forward end of the main frame 1 may embody a lever 28 fulcrumed at 29 on a two-part post 30 carried by the cross bar 8. The lever 28 is pivotally connected at 31 with a hanger 32 mounted on the top piece 16 of 90 the auxiliary frame 15. The lever 28 extends rearwardly far enough so that it is readily accessible from a seat 33 carried by the cross bars 6. A keeper 34 is supported by the cross bar 7, and the lever 28 is adapted to cooperate with the keeper. The mechanism above described and relating to the vertical adjustment of the forward end of the main frame 2 is of no particular utility 95 in connection with the topping mechanism forming the subject matter of this application. Its use, principally, is in connection with a digger for the purpose of adjusting the digger with respect to the surface of the soil.

Passing to the description of the topping mechanism, it may be stated that shoes 35 are located adjacent to the front of the machine, attention being directed especially to Figures 1, 2, 4 and 5. Each shoe 35 includes 100 an inwardly projecting flange 36 and a sharpened depending flange 37. The flanges

36 of the shoes 35 are connected at 38 to the hangers 22 as shown in Figure 3. Bearings 39 are mounted on the rear ends of the depending flanges 37 of the shoes, and receive 5 the rod or support 21 which is mounted in the arms 20 of the auxiliary frame. The horizontal flanges 36 of the shoes 35 are provided with notches 40, the function of which will be made manifest hereinafter. 10 The horizontal flanges 36 are prolonged to form deflectors 41 which, when viewed in top plan, taper toward their forward ends, as shown in Figure 2. The deflectors 41 curve upwardly, as shown in Figure 4. 15 Bearings 42 are mounted on the upper ends of the deflectors 41. An adjusting screw 43 rotates in one bearing 42 and is threaded at 44 into the other bearing, the adjusting screw having a turning head 45, engaging 20 the first specified bearing.

Vertically elongated openings 46 are formed in the vertical flanges 37 of the shoes 35, the flanges having teeth 47 which project into the openings 46. The numeral 48 25 marks a relatively fixed but adjustable blade extended transversely of the shoes 35, the blade being mounted between the teeth 47. The blade on its lower surface is supplied with transverse ribs 49, which, cooperating 30 with the teeth 47, aid in preventing the blade from moving endwise. Clamping screws 50 are threaded into the flanges 37 of the shoes 35. The upper surface of the blade 48 is provided adjacent to its ends with 35 pressions 51 receiving the lower ends of the clamping screws 50, the screws, obviously aiding to hold the blades 48 in place.

A shaft 52 is journaled for rotation in the side pieces 17 of the auxiliary frame 15, and 40 in the longitudinal bars 19, the shaft being retained, as indicated at 62, against longitudinal movement.

The shaft 52 carries a rotary topper, embodying a hub 53 and radially projecting 45 arms 54, to which transverse blades 55 are secured as indicated at 56. The blades 55 are bluntly pointed as shown in dotted lines at 94 in Fig. 2. The arms are adapted to move in the space 83 which exists between 50 the horizontal flanges 36 of the shoes 35 (note Figure 3). The blades 44 are adapted to pass through the notches 40 of the flanges 36, when the topper is rotated, it being understood that when the topper is rotated, the 55 blades 55 pass above, and in close relation to, the relatively fixed blade 48, as indicated in Figure 4.

The means for rotating the topper include 60 a sprocket wheel 57 secured to one end of the shaft 52 and cooperating with a sprocket chain 58 engaged around a sprocket wheel 59 carried by a shaft 60 supported at 61 on one of the bars 4 of the main frame 2. The shaft 60 carries a sprocket wheel 63 mounted 65 to move with the sprocket wheel 59. The

sprocket wheel 63 is engaged by a sprocket chain 64 cooperating with a sprocket wheel 65 journaled on one end of the axle 1. A ground wheel 67 is journaled on said end of the axle 1 and may be connected to the 70 sprocket wheel 65 by a pawl and ratchet mechanism 66. The construction is such that, when the machine is backed, motion will not be transmitted to the sprocket wheel 65. 75

Bearings 68 project rearwardly from the rod or support 21, and in the bearings, a shaft 69 is journaled. A shaft 70 is journaled in bearings 71 mounted on the longitudinal bars 3. The shafts 69 and 70 have 80 sprocket rollers 82 around which is engaged a rearwardly and upwardly inclined belt conveyor 72. A cross chute 73 is shown in Figure 6, the chute being inclined downwardly from one side of the vehicle toward 85 the other side thereof. The chute 73 carries cross pieces 75 engaged in and secured to the upper longitudinal bars 3 of the main frame 2. The belt conveyor 72 discharges into the cross chute 73. A sprocket wheel 90 76 is mounted on one end of the shaft 70 and is engaged by a sprocket chain 77. A shaft 78 is journaled in bearings 79 on the longitudinal bars 3, and serves as a driving means for the sprocket chain 77, the shaft 95 78 being connected operatively by a sprocket chain 80 and suitable gearing 81, with the ground wheel which is in the opposite side of the vehicle from the ground wheel 67 shown in Figure 1. 100

The drive is simple, and may be dismissed with brief comment, it being observed that the chains 77 and 64 are operated from the ground wheels of the vehicle, the chain 77 actuating the belt conveyor 72, and the chain 105 64 transmitting rotary movement to the top 64—55, by way of the sprocket chain 58 and the sprocket wheels 59 and 63.

The tops of the beets are directed between the flanges 36 of the shoes 35 by the deflectors 41. The deflectors may be adjusted toward and away from each other by manipulating the screw 43, as indicated in Figure 3, it being possible to adjust the shoes 35 toward and away from each other by sliding the parts 24 on the parts 23 of the auxiliary frame 15, the clamping screws 26 being manipulated to hold the hangers 22 in any positions to which they may have been adjusted. 110

The beets ultimately come into contact with the relatively fixed blade 48 and, as the rotary member shown in Figure 4 is operated, the blades 55 will cut off the tops of the beets. It is possible to adjust the blade 48 vertically, owing to the provision of the teeth 47, the blades being adjustable endwise, for any desired purpose, for instance, to the end that a new portion of the cutting edge of the blade may be brought into operative 115 120 125 130

position with respect to the beets. The tops of the beets are received on the conveyor 72 and are carried upwardly into the chute 73, the tops sliding out of the chute and being deposited at one side of the vehicle.

It will be understood that the flanges 37 of the shoes 35 serve as runners adapted to move along or upon the surface of the ground, or closely adjacent thereto, the deflectors 41 serving not only to direct the beet tops between the flanges 36 of the shoes, but, as well, serving to facilitate the progress of the shoes over the surface of the soil.

I claim:-

1. In a device of the class described, a vehicle embodying a frame; shoes carried by the frame; means for mounting the shoes on the frame for adjustment toward and away from each other; a rotary topper journaled on the frame and including a blade coacting with the shoes; and means for rotating the topper.

2. In a device of the class described, a vehicle including a frame; shoes; means for mounting the shoes on the frame for adjustment toward and away from each other; means for adjusting the forward ends of the shoes toward and away from each other; a

rotary topper journaled on the frame and coacting with the shoes; and means for rotating the topper.

3. In a device of the class described, a vehicle including a frame; shoes carried by the frame; a relatively fixed blade disposed transversely of the shoes; means for mounting the blade on the shoes for vertical adjustment; a topper journaled on the frame and including a blade coacting with the first specified blade.

4. In a device of the class described, a vehicle including a frame; shoes; means for connecting the shoes with the frame for transverse adjustment toward and away from each other; means for connecting the forward ends of the shoes together, thereby to secure a transverse adjustment between the forward ends of the shoes; a relatively fixed blade; means for mounting the blade on the shoes for vertical adjustment; and a rotary topper journaled on the frame, the topper including a blade coacting with said fixed blade.

In testimony that I claim the foregoing as my own, I have hereto affixed my signature.

JOSEPH WOLNY.
